CLAIM

The ornamental design for a toy construction element, as shown and described.

DESCRIPTION

FIG. 1 is a front perspective view of an ornamental design for a toy construction element showing my new design. FIG. 2 is a front view of the toy construction element of FIG. 1.

FIG. 3 is a left side view of the toy construction element of FIG. 1.

FIG. 4 is a right side view of the toy construction element of FIG. 1.

FIG. 5 is a top view of the toy construction element of FIG. 1.

FIG. 6 is a bottom view of the toy construction element of FIG. 1.

FIG. 7 is a rear view of the toy construction element of FIG. 1; and,

FIG. 8 is a rear perspective view of the toy construction element of FIG. 1.

The broken lines shown in the drawings are included for the purpose of illustrating portions of the article and form no part of the claimed design.

1 Claim, 8 Drawing Sheets
